UNITED STATES PATENT OFFICE.

THOMAS DUNCAN, OF CHICAGO, ILLINOIS, ASSIGNOR TO THE SIEMENS & HALSKE ELECTRIC COMPANY OF AMERICA, OF CHICAGO, ILLINOIS, A CORPORATION OF ILLINOIS.

ALTERNATING-CURRENT METER.

SPECIFICATION forming part of Letters Patent No. 698,666, dated April 29, 1902.

Application filed November 4, 1899. Renewed December 16, 1901. Serial No. 86,056. (No model.)

To all whom it may concern:

Be it known that I, THOMAS DUNCAN, a citizen of the United States, residing at Chicago, in the county of Cook and State of Illinois, have invented a certain new and useful Improvement in Alternating-Current Meters, (Case No. 308,) of which the following is a full, clear, concise, and exact description, reference being had to the accompanying drawings, forming a part of this specification.

My invention relates to alternating-current motor-meters, and particularly to that kind of motor-meter having a field-producing winding upon its armature that will measure the so-called "wattless" component of current in an alternating-current system of distribution such as is set forth, for example, in my application, Serial No. 735,807, filed of even date herewith.

The object of my invention is to provide an improved means for adjusting the phase of the field due to the shunt-winding.

Heretofore in applications, Serial Nos. 730,847, 730,848, 730,849, filed September 18, 1899, and Serial No. 733,290, filed October 11, 1899, I have shown and described a method of and means for measuring the wattless component of alternating current by means of motor-meters, the type of meter shown in the said application being of the induction-motor-meter type. Generally speaking, my present invention is a modification of the general class of motor-meters shown in the said applications, which is designed to ac-

complish the same general result and specifically is an improvement upon the invention disclosed in the first aforesaid copending application. In the present invention I employ a meter whose armature is provided with one of the field-producing windings and associate a phase-modifying winding in coöperative relation with the armature-winding. In practicing my invention I employ an armature having a field-winding divided into coils which are connected with a commutator somewhat analogous to the armature of a direct-current motor.

As is well known to those skilled in the art, the current of an alternating-current system

may be divided into two components, one of which is in phase with the electromotive force of the circuit, while the other has a lag of ninety degrees. This latter component constitutes the magnetizing or wattless component of the output of alternating-current central stations, and I am enabled to measure this wattless component by means of my improved commutated motor-meter.

Prior to the invention of my said copending applications the methods and means for measuring the wattless component were likely to be inaccurate and were tedious and awkward. The usual method practiced was to make a comparison of the indicated voltmperes obtained by multiplying the reading of the indicating-voltmeter by the reading of the indicating ampere-meter with the output in watts obtained from an integrating wattmeter. The latter instrument gives the average watts during a certain interval of time, and the volts and amperes are obtained by successive readings of the switchboard indicating instruments. As an illustration of what may happen in obtaining results by this crude method we may assume that the watts in a circuit as obtained through successive readings of an integrating wattmeter are five thousand, the average voltage being one thousand and the average current a little less than five amperes. The lag in the circuit would then be slight and the indications of the integrating wattmeter would give very nearly the apparent watts in the circuit. Owing to the temporary fluctuations in a circuit due to motors, the current indicated may for an instant be four amperes, which unusual fluctuation would not be apparent in the readings of the integrating wattmeter to any extent. There would then apparently be a power factor of more than one hundred per cent., the power factor representing the ratio of the true watts to the apparent watts, the apparent watts being obtained by the product of the indications of the switchboard-ammeter and switchboard-voltmeter. Improved means, therefore, for measuring accurately and instantly the lagging component of the current are important, especially where alter-

nating current is supplied to motors of considerable size and number. The difficulty in regulation which is experienced does not arise from the amount of energy which the 5 motors require, which is as a rule no more than that of direct-current motors carrying the same load, but from the influence of the lagging or wattless currents resulting from the various inductances of the circuit. Even 10 when the lagging current is measured by a comparison of volt-amperes with watts indicated by instruments of the same type and comparatively calibrated accurate results are not obtained. For example, if the volt-amperes or apparent watts exceed the true watts by only one per cent. it means that there is upon the line a wattless or magnetizing current with a strength fully fourteen per cent. of that of the energy-current. If the excess 15 is two per cent., the magnetizing-current is twenty per cent. as great as the energy-current—that is to say, if the true watts are one hundred and the apparent watts one hundred and one the lagging component, which is found by taking the square root of the difference of the squares of the true and apparent watts, would be fourteen per cent., and if the true watts are one hundred and the apparent watts one hundred and two the lagging component will be twenty. From this 20 illustration it will be apparent that very great and disturbing variations of the wattless output affect but slightly the indicated volt-amperes.

30 35 An attempt to secure approximate compensation for the lagging component always existing with induction-motors is sometimes made by the use of synchronous motors for large loads. By means of the synchronous 40 motors a leading current may be produced to balance the lagging component due to the induction-motors. The amount of leading or lagging current which the synchronous motors will induce into the system depends upon 45 the excitation of their fields, and the setting of the field-rheostats which determine this excitation is made by the crude process of what is called "adjusting for minimum current," which will reduce the difference between the apparent and true watts in the 50 circuit to a minimum. The current, however, is subject to fluctuations often as high as seventy-five per cent., and since a variation of only two per cent. in the minimum means the 55 introduction of a twenty-per-cent. magnetizing-current it is readily seen that this method of attempted regulation is not satisfactory.

In running alternating-current generators in multiple it is well known that the division 60 of the load cannot be adjusted by varying the field excitation of any one or more than one of them; nor can the load of one machine be measured by ampere-meters. Any variation of the field excitation only causes a change 65 of the voltage, and a consequent cross magnetizing-current from one machine to the other demagnetizing one and building up the

field of the other to an equality. This cross magnetizing-current should for minimum heat and maximum efficiency be kept as small 70 as possible.

By means of my invention I am enabled to employ a commutator motor-meter having a phase-modifying winding in co-operative relation with a meter-winding that is adapted to 75 measure this cross magnetizing-current accurately and readily and to measure and indicate or integrate the lagging or wattless component of an alternating-current system.

Generally speaking, commutated alternating-current motor-meters heretofore devised are provided with shunt or pressure coils forming armatures which are capable of rotation and which receive current that is approximately in phase with the impressed electromotive force. This current traversing the armature by a commutator sets up a magnetic field that is proportional to the impressed pressure and operating in conjunction with another field produced by a series 85 winding traversed by the main current produces a resultant torque which is proportionate to the real watts, and assuming that the electromotive force is maintained constant the torque will vary as the cosine of the angle between the electromotive force and current or the magnetism of the shunt and series windings. In practicing my present invention I preferably employ a commutated meter whose armature is composed of windings that are adapted to be connected in bridge of supply-mains by means of a commutator and brushes, as it is undesirable to include the armature-winding in circuit, so as to receive the main current or a fraction 90 thereof as it is conveyed to the translating devices. I associate a phase-modifying winding in co-operative relation with the armature. I thus provide means by which the torque of the commutated meter will be maximum when the angle of lag between the electromotive force and the current is ninety degrees. In a commutated wattmeter the torque will be zero when the angle of lag is ninety degrees. Thus in a commutated wattmeter the greatest turning effort is exerted when there is no difference in phase between the current and electromotive force, and no turning effort is exerted when there is a difference of ninety 100 degrees in phase between the current and electromotive force, as the current is then wattless, whereas in the meter of my invention the torque is greatest when the current is wattless and zero when there is no lag.

Where induction-meters are employed to 105 measure the wattless energy, the magnetism which represents the electromotive force is maintained in phase with the electromotive force, while in the preferred form of commutated type of motor-meter that I employ the 110 pressure magnetism must be maintained in quadrature with the electromotive force, so that when the current in the work-circuit lags ninety degrees it will be in phase with the 115

pressure magnetism, and both being in phase the torque will be maximum. This torque will vary from zero to maximum as the angle of lag varies from zero to ninety degrees. Commutated meters might be devised, however, wherein it would not be essential to maintain the pressure magnetism in quadrature with the line or impressed electromotive force; but in all forms of commutated meters for measuring wattless components the fields due to the series and shunt windings should be in phase when the angle of lag is ninety degrees and should vary the torque upon variation in the angle of lag, these fields being in quadrature when there is no lag in the circuit.

I will explain my invention more particularly by reference to the following drawings, illustrating the preferred embodiment thereof, in which—

20 Figure 1 is a diagrammatic view showing a meter and its circuit connections in accordance with my invention. Fig. 2 is a vector diagram showing the relations in the circuits of a system embodying the invention. Fig. 25 3 shows a modified form of meter with its connections. Fig. 4 shows another modified form of meter with its connections.

Like parts are indicated by similar letters of reference in the different views.

30 A source of alternating current 1 supplies current to translating devices 2. An armature 3, composed of coils of fine wire, is mounted upon the rotating spindle 4, series coils 5 being included in series with one of the main conductors extending from the source of alternating current to the translating devices. In Figs. 1 and 4 the coils 5 are in series with each other. In Fig. 3 they are in multiple. These series coils are located upon opposite sides of the spindle 4, the armature projecting within the interior of the said coils. Said series winding is thus included in series with the translating devices and sets up a magnetic field that is proportional to the current strength. The coils of the armature 3 are connected with the segments of the commutator 6 in a usual way, the commutator-brushes 7 serving to include the armature in a bridge between the main leads extending from the generator. In order to have the meter accurately measure the wattless or magnetizing components in alternating-current power-circuits, I provide means whereby a torque varying as the sine of the angle of lag is created. This I accomplish in commutated meters by bringing the fields due to the series and shunt windings in phase when the current in the work-circuit lags ninety degrees, thereby to produce the maximum torque and bring about a variation of the phase difference between these fields when the current ceases to lag ninety degrees.

In the particular embodiment of the invention shown the pressure-field should be maintained in quadrature with the line-pressure,

so that the torque will vary as the sine of the angle of lag of the current through the translating devices and be zero when the current and pressure are in phase when there is no lag in the work-circuit. I cause the revolute armature to create a magnetic field that is approximately in quadrature with the pressure by passing current to the armature through an impedance-winding 8, which causes current through the armature to lag nearly ninety degrees, and using my improved supplemental means for bringing the pressure-field into exact quadrature with the pressure, as it is impracticable to effect this adjustment by the winding 8 alone, owing to the presence of resistance. I employ a winding 9, which is preferably stationary, and place it in cooperative and magnetic coaxial relation with the armature and use reactance 85 for adjusting the phase of the current in said winding 9. In the arrangement shown in Fig. 1 I include a portion of the winding 8 in a closed circuit with the winding 9, adjusting ohmic resistance 10 being included in said closed circuit. The result of these instrumentalities is illustrated in Fig. 2, where *a b* represents the line-pressure; *a c*, the magnetism due to the armature; *a d*, the magnetism due to current in that portion of the winding 95 8 which flows through the stationary shunt-winding 9; and *a e* the resultant magnetic field of force representing the impressed electromotive force in quadrature with *a b*, being the resultant of the magnetism *a c* of the armature and the magnetism *a d* of the winding 9. The magnitude of the component *a d* is adjusted by means of the resistance 10.

In the apparatus shown in Fig. 3 I cause the current in the winding 9 to lag one hundred and eighty degrees or more behind the impressed electromotive force by winding about the impedance-winding 8 a few turns of wire 11, which constitute a secondary, and including the secondary 11 in circuit with the winding 9. The resistance 10 serves to adjust the current. The same result might be accomplished by including the winding 9 in a closed circuit with an adjusting resistance 12. (Shown in dotted lines.) In this arrangement the armature is used as an inducing-winding instead of the winding 8.

In the apparatus shown in Fig. 4 I supply the winding 9 directly from the mains, between which it is included in bridge, the resistance 10 serving to adjust the amount of current passing through said winding. In this case the connection of the winding 9 with the circuit should be reversed with respect to the terminal connections of the armature 125 with the circuit to secure a phase displacement of one hundred and eighty degrees.

As is shown in Figs. 1, 3, and 4, the winding 9 is divided into two coils placed on opposite sides of the shaft or spindle 4. The 130 coils of winding 9 are at right angles to the series coils 5 to prevent mutual induction.

In Fig. 3 the magnetic axis of the armature 3 is indicated by the dotted lines wx , which is also the magnetic axis of the shunt-coils 9, while the magnetic axis of the series or ampere coils is indicated by the dotted line yz .

While I have herein shown and particularly described some embodiments of my invention, it is obvious that other embodiments thereof may be devised without departing from the spirit of the invention, and I do not therefore wish to be limited to the precise apparatus herein shown and particularly described; but,

Having thus described my invention, I claim as new and desire to secure by Letters Patent—

1. In an alternating-current meter, the combination with a revoluble armature having a field-producing winding, of a second winding in coöperative relation therewith for producing a resultant magnetic field in quadrature with the pressure, substantially as described.
2. In an alternating-current meter the combination, with a revoluble armature having a field-producing winding, of a second stationary winding in coöperative relation therewith for producing a resultant magnetic field in quadrature with the pressure, substantially as described.
3. In an alternating-current meter, the combination with a revoluble armature having a field-producing winding, of a second winding in coöperative relation therewith for producing a resultant magnetic field in quadrature with the pressure, and a stationary field-winding associated with the armature, substantially as described.
4. In an alternating-current meter, the combination with a revoluble armature having a field-producing winding, of a second stationary winding in coöperative relation therewith for producing a resultant magnetic field in quadrature with the pressure, and a stationary field-winding associated with the armature, substantially as described.
5. In an alternating-current motor, the combination with a pressure-winding, of a second field-winding, one of the said windings being revoluble, means for independently supplying current to the said windings from an external source and a phase-modifying winding in coöperative relation with the pressure-winding, substantially as described.
6. In an alternating-current motor, the combination with a pressure-winding, of a second field-winding, one of the said windings being revoluble, means for independently supplying current to the said windings from an external source and a phase-modifying stationary winding in coöperative relation with the pressure-winding, substantially as described.
7. In an alternating-current motor, the combination with two field-windings, one of which is movable, of a phase-modifying winding in coöperative relation with one of said field-windings adapted to maintain the phase of the

field due thereto substantially in quadrature with the pressure, substantially as described.

8. In an alternating-current motor, the combination with two field-windings, one of which is movable, of a phase-modifying winding in coöperative relation with one of said field-windings adapted to maintain the phase of the field due thereto substantially in quadrature with the pressure, and a commutator for supplying current to the movable winding, substantially as described.

9. In an alternating-current meter, the combination with pressure and ampere field-windings, one of which is movable, of a phase-modifying winding in coöperative relation with the pressure-winding and adapted to maintain the resultant magnetic field due to the latter winding substantially in quadrature with the pressure, substantially as described.

10. In an alternating-current meter, the combination with pressure and ampere field-windings, one of which is movable, of a phase-modifying winding in coöperative relation with the pressure-winding and adapted to maintain the resultant magnetic field due to the latter winding substantially in quadrature with the pressure, and a commutator for including the movable winding in circuit, substantially as described.

11. In an alternating-current meter, the combination with pressure and ampere field-windings, the pressure-winding being rotatable, of a phase-modifying winding in coöperative relation with the pressure-winding for maintaining the phase of the resultant magnetism due to the pressure-winding substantially in quadrature with the pressure, substantially as described.

12. In an alternating-current meter, the combination with pressure and ampere field-windings, the pressure-winding being rotatable, of a phase-modifying winding in coöperative relation with the pressure-winding for maintaining the phase of the resultant magnetism due to the pressure-winding substantially in quadrature with the pressure, and a commutator for including the pressure-winding in circuit, substantially as described.

13. In an alternating-current meter, the combination with pressure and ampere field-windings, the pressure-winding being rotatable, of a phase-modifying winding in coöperative relation with the pressure-winding for maintaining the phase of the resultant magnetism due to the pressure-winding substantially in quadrature with the pressure, and adjusting means for determining the current in the phase-modifying winding, substantially as described.

14. In an alternating-current meter, the combination with pressure and ampere field-windings, the pressure-winding being rotatable, of a phase-modifying winding in coöperative relation with the pressure-winding for

5 maintaining the phase of the resultant magnetism due to the pressure-winding substantially in quadrature with the pressure, a commutator for including the pressure-winding in circuit, and adjusting means for determining the current in the phase-modifying winding, substantially as described.

15. In a system of distribution, the combination with an alternating-current generator, of pressure and ampere windings in circuit therewith, the pressure-winding being movable to have it serve by its motion to measure the wattless component of the current, of a phase-modifying winding supplied with current also from said source, and being in cooperative relation with the pressure-winding to produce and maintain a field substantially in quadrature with the pressure, substantially as described.

20. 16. In a system of distribution, the combination with an alternating-current generator, of pressure and ampere windings in circuit therewith, the pressure-winding being movable to have it serve by its motion to measure the wattless component of the current, of a phase-modifying winding supplied with current also from said source, and being in cooperative relation with the pressure-winding to produce and maintain a field substantially 25 in quadrature with the pressure, and a commutator for including the pressure-winding in circuit, substantially as described.

17. In a system of distribution, the combination with an alternating-current generator, of pressure and ampere windings in circuit therewith, the pressure-winding being movable to have it serve by its motion to measure the wattless component of the current, of a phase-modifying winding supplied with current also from said source, and being in cooperative relation with the pressure-winding to produce and maintain a field substantially 40 in quadrature with the pressure, the phase-modifying winding and the ampere field-winding being at right angles to prevent mutual induction, substantially as described.

45. 18. In a system of distribution, the combination with an alternating-current generator, of pressure and ampere windings in circuit therewith, the pressure-winding being movable to have it serve by its motion to measure the wattless component of the current, of a phase-modifying winding supplied with current also from said source and being in cooperative relation with the pressure-winding to produce and maintain a field substantially 50 in quadrature with the pressure, and a commutator for including the pressure-winding in circuit, the phase-modifying winding and 55 the ampere field-winding being at right angles to prevent mutual induction, substantially as described.

60. 19. In a system of alternating-current distribution, the combination with an alternating-current generator, of a rotatable pressure-winding for measuring by its motion the

wattless component of alternating currents, inductance in circuit with said winding, a phase-modifying winding in coöperative relation with the pressure-winding for maintaining the resultant field due thereto substantially in quadrature with the pressure and an ampere-winding coöperating with the pressure-winding to produce a torque varying as the sine of the angle of lag between the 70 current and pressure, substantially as described.

75. 20. In a system of alternating-current distribution, the combination with an alternating-current generator, of a rotatable pressure-winding for measuring by its motion the wattless component of alternating currents, inductance in circuit with said winding, a phase-modifying winding in coöperative relation with the pressure-winding for maintaining 80 the resultant field due thereto substantially in quadrature with the pressure, an ampere-winding coöperating with the pressure-winding to produce a torque varying as the sine of the angle of lag between the current and 85 pressure, and adjusting means for determining the current in the phase-modifying winding, substantially as described.

90. 21. In a system of alternating-current distribution, the combination with an alternating-current generator, of a rotatable pressure-winding for measuring by its motion the wattless component of alternating currents, inductance in circuit with said winding, a phase-modifying winding in coöperative relation 95 with the pressure-winding for maintaining the resultant field due thereto substantially in quadrature with the pressure, an ampere-winding coöperating with the pressure-winding to produce a torque varying as the sine 100 of the angle of lag between the current and pressure, and a commutator for including the pressure-winding in circuit, substantially as described.

105. 22. In a system of alternating-current distribution, the combination with an alternating-current generator, of a rotatable pressure-winding for measuring by its motion the wattless component of alternating currents, inductance in circuit with said winding, a phase-modifying winding in coöperative relation 110 with the pressure-winding for maintaining the resultant field due thereto substantially in quadrature with the pressure, an ampere-winding coöperating with the pressure-winding to produce a torque varying as the sine 115 of the angle of lag between the current and pressure, adjusting means for determining the current in the phase-modifying winding, and a commutator for including the pressure-winding in circuit, substantially as described.

120. 23. In a system of alternating-current distribution, the combination with an alternating-current generator, of a rotatable pressure-winding for measuring by its motion the wattless component of alternating currents, inductance in circuit with said winding, a phase- 125

130.

modifying winding in coöperative relation with the pressure-winding for maintaining the resultant field due thereto substantially in quadrature with the pressure, an ampere-
5 winding coöperating with the pressure-wind-
ing to produce a torque varying as the sine
of the angle of lag between the current and
pressure, and adjusting means for determin-

ing the current in the phase-modifying wind-
ing, substantially as described.

In witness whereof I hereunto subscribe my
name this 31st day of October, A. D. 1899.

THOMAS DUNCAN.
